H. T. LANG

VACUUM CLEANER

Filed Aug. 7, 1922

Fig. 2.

Fig. 6.

Inventor:
Henry T. Lang,
by Allen & Davis
His Attorney

UNITED STATES PATENT OFFICE.

HENRY T. LANG, OF CLEVELAND, OHIO, ASSIGNOR TO ELECTRIC VACUUM CLEANER COMPANY, INC., A CORPORATION OF NEW YORK.

VACUUM CLEANER.

Application filed August 7, 1922. Serial No. 579,982.

To all whom it may concern:

Be it known that I, HENRY T. LANG, a citizen of the United States, residing at Cleveland, in the county of Cuyahoga, State 5 of Ohio, have invented certain new and useful Improvements in Vacuum Cleaners, of which the following is a specification.

The present invention relates to vacuum cleaners of the portable motor driven type 10 wherein a rotatable agitating device such as a brush is provided in the section nozzle of the cleaner which device may be driven by the same motor as that which drives the suction fan.

15 The object of my invention is to provide an improved structure and arrangement of brush mounting, and for a consideration of what I believe to be novel and my invention, attention is directed to the accompanying 20 description and the claims appended thereto.

In the drawing, Fig. 1 is a side elevation of a vacuum cleaner embodying my invention; Fig. 2 is a front view with the front 25 nozzle wall broken away and certain parts shown in section; Fig. 3 is a detail end view of a brush and brush mounting; Fig. 4 is a sectional view taken on line 4—4, Fig. 3; Fig. 5 is a bottom plan view of a part of 30 the suction nozzle illustrating a nozzle guard structure; and Fig. 6 is a sectional view of the lower portion of the nozzle.

Referring to the drawing, 10 indicates the motor, 11 the fan casing and 12 the suction 35 nozzle of a portable motor driven electric vacuum cleaner. The cleaner is supported on a rear wheel 13 carried in a bracket 14 fixed to the motor casing and by two forward wheels 15 carried by a frame 16. Frame 16 is pivoted to the end walls of the 40 suction nozzle as indicated at 17 and is provided with a screw 18 for adjusting the height of the nozzle from the floor. The handle for propelling the cleaner is indicated at 19 and the dust bag is indicated at 20. On the end of the motor shaft is a pulley 21 connected by a belt 22 to a pulley 23 on the shaft of a brush 24 located in the nozzle of the cleaner. The structure 45 so far described may be taken as typical of any suitable vacuum cleaner structure, the arrangement of the mounting for forward wheels 15 and the adjustment thereof form-

ing the subject matter of an application of Otto Brintzenhofe, Serial No. 579,977 filed 55 on even date herewith.

Referring now to the brush mounting, the ends of the brush shaft are fixed in ferrules 25 from which project stub shafts 26, and surrounding stub shafts 26 are bearing 60 sleeves 27 provided with bearing linings 28. Bearing linings 28 are permanently fixed in sleeves 27 and terminate short of the outer ends of the sleeves to provide recesses 29 in which are located the heads of pins 30 65 fastened in holes 31 in the ends of the stub shafts. Pins 30 serve to permanently fasten bearing sleeves 27 to the stub shafts and it will be noted that the heads of the pins run on the ends of bearing linings 28 and that 70 they do not touch the inner surfaces of sleeves 27. The bearing sleeves form in substance a part of the brush structure and when held stationary the brush may be 75

Formed integral with bearing sleeves 27 are cup-shaped extensions 32 which surround small flanges 33 on ferrules 25 and form guards to prevent the entrance of threads and dirt to the bearing. Projecting from 80 each flange 33 are one or more pins 34 which serve to stir up any dust which tends to lodge inside the guard cups and cause it to work out from the spaces between flanges 33 and the cups. Air in being drawn into 85 the cleaner passes these spaces and the dust, since it is kept stirred up by the pins, is caught by the air and carried to the dust bag.

On the inner surface of the end walls of 90 the nozzle are pads 35 to which are fastened bearing holders 36. Each bearing holder comprises a disk 37 of suitable material, such as fibre, provided with one or more curved recesses adapted to receive the bearing sleeves 27. In the present instance two recesses 38 and 39 are shown, the recess 38 being deeper than the recess 39. Fixed to disk 37 is a spring clip 40 the two ends of 95 which project over recesses 38 and 39 and are provided with sharp inturned edges 41 adapted to engage the knurled surfaces of bearing sleeves 27. At the center of disk 37 is a countersunk opening 42 to receive a 100 screw 43 for fastening the disk to pads 35 105 and diametrically opposed to recesses 38 and

39 and holes 44 which receive the ends of pins 45 projecting from pads 35. Pins 45 serve to correctly position the bearing holders and to hold them from turning.

5 The purpose of providing recesses 38 and 39 of different depths is to permit of adjustment of the brush. When the brush is new and the bristles are of full length, the brush bearings are put into the deeper recesses 38, the bearing holders at that time being so positioned that recesses 38 open downwardly as shown in Fig. 3. When the bristles in the brush become worn, the brush is removed, screws 43 are loosened so the bearing holders can be moved from engagement with pins 45, and the holders are turned so recesses 39 face downwardly, the other holes 44 then coming into line with pins 45. Screws 43 are then again tightened 20 to fasten the bearing holders in their new positions and the brush is again put into place. The ends of spring clip 40, while they hold the brush bearings firmly in recesses 38 or 39, yield sufficiently to permit 25 of the ready removal and insertion of the brush.

In connection with the nozzle of the cleaner there is provided a brush guard comprising spaced fingers 46 which extend 30 across the mouth of the nozzle to prevent the carpet from being sucked too far into the mouth. Fingers 46 are pivoted at one end to the forward lip of the nozzle mouth by pins 47 and the other ends are fastened 35 together by a strip 48, being shown in the present instance as formed integral with such strip. Strip 48 lies along the back surface of the rear lip of the nozzle and on such surface are two rounded projections 49 which rest in sockets 50 in strip 48. Projections 49 may be formed by fastening 40 small, round-headed rivets in the nozzle wall and sockets 50 may be formed by striking out beads in strip 48. When it is desired to remove the brush, the brush guard is sprung loose from projections 49 and 45 swung away from across the nozzle mouth turning on pivot pins 47. To return it to normal position, it is swung back again 50 on its pivot and snapped into engagement with projections 49.

Since the brush bearings are a part of the brush structure they are self-aligning. That is, when the bearings are clamped in 55 the bearing holders they are bound to assume positions in correct alignment with the brush and its stub shafts because they form a part of the brush structure. If the bearing holders are somewhat out of alignment 60 this will not affect the positioning of the brush because the spring clips 40 will yield sufficiently to permit the bearings to assume correct positions.

65 In vacuum cleaners having motor driven brushes there is always more or less wear

on the brushes and the bearings. With my arrangement the brush and bearings may be simultaneously replaced as a unit with the minimum of trouble and without removing and replacing any parts permanently attached to the cleaner proper.

In accordance with the provisions of the patent statutes, I have described the principle of operation of my invention, together with the apparatus which I now consider 75 to represent the best embodiment thereof, but I desire to have it understood that the apparatus shown is only illustrative and that the invention may be carried out by other means.

80 What I claim as new and desire to secure by Letters Patent of the United States, is:—

1. The combination with a vacuum cleaner having a suction nozzle, of a dust-agitating device in the nozzle provided with stub shafts at its ends, bearings for the stub shafts which bearings are permanently attached to the stub shafts, and bearing holders fixed to the suction nozzle for holding said shaft bearings, said bearing holders comprising members having slots provided with open sides and means for holding the bearings in the slots.

2. The combination with a vacuum cleaner having a suction nozzle, of a dust-agitating device in the nozzle provided with stub shafts at its ends, bearing sleeves attached to said stub shafts, disks attached to the suction nozzle and provided with recesses having open sides to receive said bearing sleeves, and spring clip means for holding said bearing sleeves in said recesses.

3. The combination with a vacuum cleaner having a suction nozzle, of a dust-agitating device in the nozzle, a shaft for the device, bearing sleeves for the shaft, means fastening said sleeves on the shaft, disks fixed to the suction nozzle and provided with recesses of varying depths, and means for holding the bearing sleeves in 105 said recesses.

4. An agitating device for the suction nozzle of a vacuum cleaner, said device having projecting stub shafts, bearing sleeves in which said stub shafts are journaled, means fastening said bearing sleeves on the stub shafts, and cup-shaped guards carried by the inner ends of said sleeves close to the ends of the agitating device.

5. An agitating device for the suction nozzle of a vacuum cleaner, said device having projecting stub shafts bearing sleeves in which said stub shafts are journaled, means fastening said bearing sleeves on the stub shafts, cup-shaped guards carried by the inner ends of said sleeves close to the ends of the agitating device, and pins for stirring up particles of dust to prevent their lodging in the guards.

6. In combination, an agitating device, stub shafts projecting from the ends thereof, bearing sleeves for said stub shafts, means fixing the bearing sleeves on the stub shafts, cup shaped members carried by the bearing sleeves, said members surrounding the ends of the agitating device and having a clearance therewith, and means for stirring up foreign particles tending to lodge in such clearance space. 10
- In witness whereof, I have hereunto set my hand this first day of August, 1922.

HENRY T. LANG.
